UNITED STATES PATENT OFFICE.

DAVID BERGE, OF TRONDEJEM, NORWAY.

PROFILOGRAPH.

Application filed April 18, 1924. Serial No. 707,504.

To all whom it may concern:

Be it known that I, DAVID BERGE, a subject of the King of Norway, residing at Brinken 10, Trondhjem, Norway, have invented certain new and useful Improvements in Profilographs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to profilographs, i. e. apparatus for recording profiles of the ground, and the object of the invention is to provide an apparatus of this kind, which enables profiles being recorded quickly, with a minimum of costs, and with a sufficient degrees of accuracy. To this end I employ a measuring compass and a recording board on which the result of the measuring is directly printed.

20 25 In the following the invention will be explained with reference to the accompanying drawings, in which:

Fig. 1 is a diagrammatical side view of a measuring compass in accordance with my invention, together with the recording board cooperating therewith.

30 Fig. 2 is a corresponding end view.

Fig. 3 is a sectional view of the head piece of the compass and Fig. 4 is a side view 35 of the same.

Fig. 5 is a side view of the said head with its points in positions corresponding to that of Figs. 1 and 2.

Fig. 6 is a diagram illustrating the best 40 way of profilating the broken ground shown therein.

Referring to the drawings (Figs. 1 and 2), A and B are the foot points in the ground of the legs 1 and 2 of the profilating compass. The leg 1 preferably is made in two parts and is provided with a detachable sleeve. 3 is a marking or recording board, provided along its upper edge with a rail 4 carrying a spirit or other level, and serving as abutment for the upper horizontal edge of the recording sheet. The board 3 is carried by aid of a handle 5 (Fig. 2), a metal plate 6 serving as a bearer for the recording sheet. A' and B' are sharp points adapted to be pressed against the recording sheet on the recording board in

order to mark thereon the corresponding points. The marking point A' is fastened to a block or head 7, which by aid of a clamping screw 9 is fastened to the hinge bolt 8, said bolt being firmly connected to the leg 2 of the compass. The other marking point B' is fastened to the leg 1. A shoulder 11 on the hinge bolt 8 keeps the legs 1 and 2 together. The end of the hinge bolt 8 is supported by an annular journal 12, fastened to the head of the leg 1 by aid of three clamping screws 13. The points A' B' as shown in the drawings are arranged parallel to the hinge bolt 8 of the compass legs 1 and 2. C is the central point of the hinge bolt. The profilating compass works on the principle of a reduction compass, the proportions of the legs being:

$$\frac{A'C}{CB} = \frac{B'C}{CA} = \frac{1}{K}$$

If for instance the profiles are to be reduced to a scale of 1:200, the above proportion of

$$\frac{1}{K} = \frac{1}{200}$$

may suitably be made

$$\frac{0.8 \text{ cm.}}{160 \text{ cm.}}$$

Further

$$\frac{A'B'}{AB} = \frac{1}{k}$$

wherefrom is deducted that when the lower ends of the legs are placed on the points A and B, respectively in the ground, the distance between the points A' B' will be 1/200 of this distance AB, and the angle of slope of the line A' B' will be equal to that of the line AB.

From this will be understood that when the point A' is pressed against a corresponding point on the marking sheet of the recording board 3, and this board is then turned about the point A' until the spirit level fastened to this board is in its level position, and the point B' in this position of the board is pressed against the marking paper sheet, the point B of the ground is thereby correctly marked off on the recording sheet.

When continuing the profilating operation the points B and B' are used in the same manner as A and A', whereby a third point is marked on the recording sheet, and so on.

For the handling of this apparatus only one person is needed. He carries the recording board in one hand, and the compass in the other.

- 5 If the apparatus is to work with a permanent length of steps (i.e. with a permanent distance between the lower ends of the legs) it may be simplified, the hinge bolt 8 being then superfluous, and it being then sufficient
 10 to fasten the two point A'B' permanently, for instance on one of the legs, in a suitable length above the ground and on a line parallel with that through the lower ends of the legs 1 and 2.
 15 In the executional form of the apparatus illustrated in the drawings the two legs of the compass are of different length for instance 3 and 1.5 meters. These lengths may be varied at will, provided that they conform
 20 with the equations given in the foregoing. If, however, the legs are made of equal lengths the points A'B' are liable to collide, when the legs are to be swung past one another. The use of one long leg also
 25 facilitates reaching comparatively inaccessible points in the ground.

When the apparatus is to be used it is placed as illustrated in Fig. 1, and the points A'B' are pressed against the recording
 30 paper sheet on the marking board—or vice versa—thereby marking the points AB on the paper. The operation is then continued by alternately swinging the legs of the compass. The points marked off on the latter
 35 are eventually united by a line—the profile line.

The ground profile shown in Fig. 6 illustrates the way in which it may be recorded by aid of the apparatus. The points A B
 40 having been marked on the recording sheet, the long leg 1 is swung successively to the points C, D and E, the corresponding points being recorded on the recording sheet.

Claims—

1. A profilating apparatus including a 45 two-legged compass, the lower ends of said legs forming points adapted to be placed in contact with the ground, two marking points on the compass arranged on a line parallel to a line drawn through the points of the 50 legs, and a recording board adapted to carry a record sheet and provided with leveling means to permit the operator to maintain the board in a predetermined position while pressing the board against said marking 55 points.

2. A profilating apparatus including a compass provided with two pivotally connected legs, the lower ends of said legs being adapted to contact with the ground, a marking point for each leg fixed to move with the leg with which it is associated, said marking points being spaced from each other and being parallel to the axis of the pivot connecting the legs, and a recording board 60 for the marking points adapted to support a record sheet and provided with a spirit level to permit said sheet to be brought in proper position relatively to the horizontal. 65

3. A profilating apparatus including a compass having two legs, a pivot pin fixed to one of said legs, the other leg being free to swing about the pivot pin, a clamping member fixed to the pivot pin, a marking point carried by the clamping member, a sleeve forming part of the leg which swings about the pivot pin, a bearing for the pivot pin, adjustable members connected to the sleeve and engaging said bearing, and a second marking point carried by said sleeve, 70 said marking points being spaced from each other and from the axis of said pivot pin, 75 and being arranged parallel to said axis. 80

In testimony that I claim the foregoing as my invention, I have signed my name.

DAVID BERGE
